DESIGN FOR A FINGER RING MOUNTING

Julius Dinhofer, New York, N. Y.

Application February 16, 1938, Serial No. 75,177

Term of patent 3½ years

To all whom it may concern:

Be it known that I, Julius Dinhofer, a citizen of the United States and a resident of the city, county, and State of New York, have invented a new, original, and ornamental Design for Finger Ring Mountings, of which the following is a specification, reference being had to the accompanying drawing, forming a part hereof, in which

Fig. 1 is a side elevation of a finger ring mounting embodying the new design, and Fig. 2 is a plan view of the same.

I claim:

The ornamental design for a finger ring mounting, as shown.

JULIUS DINHOFER.
